UNITED STATES PATENT OFFICE.

JOHN McDERMOTT, OF KENDALL CREEK, PENNSYLVANIA, ASSIGNOR OF
ONE HALF TO GEORGE E. BENNINGHOFF, OF SAME PLACE.

GAS-ALARM BURNER.

SPECIFICATION forming part of Letters Patent No. 374,614, dated December 13, 1887.

Application filed March 24, 1887. Serial No. 232,260. (No model.)

To all whom it may concern:

Be it known that I, JOHN McDERMOTT, a citizen of the United States, residing at Kendall Creek, in the county of McKean and State 5 of Pennsylvania, have invented certain new and useful Improvements in Gas-Alarm Burners; and I do hereby declare the following to be a full, clear, and exact description of the invention, such as will enable others skilled in 10 the art to which it appertains to make and use the same.

My invention relates to apparatus for utilizing natural gas for illuminating, heating, and other purposes; and the object of my invention 15 is to provide means whereby an acoustic alarm may be given upon the occurrence of excessive pressure.

To the above purpose my invention consists in a reed or other sounding alarm placed 20 within the current of gas and so arranged as to be brought into operation when the pressure of gas becomes abnormal.

In order that my invention may be fully understood, I will proceed to describe it with 25 reference to the accompanying drawings, in which—

Figure 1 illustrates my invention applied to a Bunsen burner. Fig. 2 illustrates my invention applied to a heating or cooking apparatus. Fig. 3 is a side elevation of my improved attachment. Fig. 4 is a longitudinal section of the same. Fig. 5 is a detached view of the slide. Fig. 6 is a sectional view on the line 6 30 of Fig. 3.

My improvement is designed to be used in connection with all of the various forms of illuminating and heating or cooking apparatus in which natural or other gas under pressure is utilized, so that an attendant may be instantly 35 warned of the occurrence of excessive pressure, and thus promptly control the flow of gas.

In the said drawings, A in Fig. 1 designates a Bunsen burner, and B in Fig. 2 designates a heating or cooking apparatus, both being 40 supplied through a pipe, C.

In the arrangement shown in Fig. 2 the pipe C is bent or curved circuitously, as indicated at e, and a valve, c', is placed as shown, so as to control the pressure and render it uniform.

D designates a tubular casing internally screw-threaded at its ends, as indicated at d d, and having orifices formed in its sides, as shown at d'. Within this tubular casing is placed a diaphragm, E, transversely grooved, 55 as at e, and lying contiguous to the openings or apertures d'. At any suitable point of the diaphragm E is formed a small hole, e', and said diaphragm is also formed with a larger aperture, e".

F is a slide which is inserted into one of the openings or orifices d', and slides along the groove e, said slide being formed with an opening or aperture, f', corresponding in size with the aperture e' of the diaphragm E, and registering therewith when the slide is moved into closed position. A flat enlarged head, f", is formed upon the outer end of the slide F, so as to afford a convenient hold for moving the same.

G designates the casing of a reed, which is inserted into the hole or aperture e", said casing being of the form shown. Any desired form of reed may be used; but the form shown is usually preferable.

From the above description it will be seen that when the slide is forced inward the gas will flow only through the opening in the slide and the smaller opening in the diaphragm. When the attendant is required to leave the apparatus, or when he is, for any reason, prevented from watching it, he pulls the slide either wholly or partially outward, so as to expose the opening e'. In this event the gas flows equally through both apertures in the 85 diaphragm, and normally the alarm is not sounded; but when excessive pressure occurs the surplus gas rushing through the opening e' sounds the alarm. The necessary mixture of air with the gas is permitted by the openings d, before referred to.

Having thus described my invention, what I claim as new, and desire to secure by Letters Patent, is—

1. An improved attachment for gas-conductors, consisting of an acoustic signal located within the current of gas, and operated by abnormal pressure of gas, substantially as and for the purpose described.

2. An improved attachment for natural-gas

conductors, consisting of a reed or vibratory tongue located within the current of gas and operated by excessive pressure of the gas, substantially as and for the purpose set forth.

5 3. The combination, with the tubular casing, with its apertures d' , and the diaphragm with its smaller and larger openings $e' e''$, of the alarm-casing set over the larger opening, e'' , and the slide F, having an aperture, f' , to register with

the smaller opening in the diaphragm, substantially as and for the purpose specified.

In testimony whereof I affix my signature in presence of two witnesses.

JOHN McDERMOTT.
